REFRIGERATOR LATCH

Lloyd L. Anderson and Robert E. Johnson, Grand Rapids, Mich., assignors to Winters & Cramp-ton Corporation, Grandville, Mich., a corpora-tion of Michigan

Application June 10, 1946, Serial No. 675,720

5 Claims. (Cl. 292—63)

1

This invention is directed to a particularly simply constructed, economically manufactured and effective latch structure, adapted to be used on refrigerator doors, and having a spring actuated latch bolt to engage with a keeper therefor, carried on the adjacent casing or housing of the refrigerator. In the present invention, insofar as the latch mechanism is concerned, it is constructed of three major parts, all readily and economically made from sheet metal, with the utilization of pins for connecting the parts together, and simple springs associated with the parts in the fully assembled latch structure. The latch bolt is automatically retracted when a door, carrying the latch, is closed, whereupon a beveled end of the latch bolt engages with and rides over the keeper. The latch bolt is released by an outward pull upon a handle, or the like, the movement of which withdraws a rod, said rod in its normal position interposing a stop against disconnection of the bolt with the keeper. The present invention is concerned, among other things, with improvements in the way of simplifying and bettering and more economically producing latches of the character, for example, disclosed in my prior patents having Numbers 2,136,662, issued November 15, 1938; 2,186,795, issued January 9, 1940, and 2,252,591, issued August 12, 1941.

In the present invention, the latch structure may be directly mounted at the inner side of the refrigerator door and the keeper at the inner side of the casing near the front face of a side of such casing, with a minimum and nearly complete absence of cutting away to make room for the installation of the latch so far as the refrigerator structure, either of the door or casing, is concerned. The latch is concealed when the door is closed, with all that is exposed in the front being the latch releasing handle or equivalent. It is an object and purpose of the present invention to provide a novel, simply constructed and economical latch structure of the character stated, with which the door may be closed to a tightly closed position and held with a required compression of the sealing gasket between the door and the refrigerator casing, and with no undue increase in strength of the latch bolt spring, the force of which is exerted to hold the latch bolt in operative connection or relation to the keeper; and further, to provide a latch structure in which the bolt may be readily released without compressing the latch bolt projecting spring, the releasing being accomplished by a relatively light pull upon the handle in an out-

ward direction, therefore, in the direction of the movement of the door for opening.

An understanding of the invention may be had from the following description, taken in connection with the accompanying drawings, in which,

Fig. 1 is a fragmentary horizontal section through the free vertical edge portion of a refrigerator door and its associated side of the refrigerator casing with the door in closed position, the latch structure being shown in plan, and showing a handle operated means of releasing the latch.

Fig. 2 is a fragmentary transverse section through the door, the latch being shown in end elevation, and another construction of latch release illustrated, partly in section and partly in elevation.

Fig. 3 is a rear elevation of the latch, viewing the same from the inner side of the door.

Fig. 4 is an elevation from the opposite side of the latch structure.

Figs. 5, 6, 7 and 8 are longitudinal horizontal sections through the latch showing the mechanism within the latch housing in four different positions, which positions may be occupied by the interior latch mechanism at different stages of the latch operation.

Figs. 9 and 10 are transverse, vertical sections upon the planes 9—9 and 10—10 respectively of Fig. 5 looking in the direction indicated, and

Fig. 11 shows in perspective the three major parts or elements of the latch structure in separated or disassembled condition.

Like reference characters refer to like parts in the different figures of the drawings.

As illustrated in Fig. 1, the front portion of a side 1 of a refrigerator casing is shown as having associated therewith a door 2 closed to shut the open side of the refrigerator, and with a compressible gasket 3 between the front face of said side 1 and the adjacent rear face portion of the face of the door 2. Such gasket shown secured to the casing extends entirely around the door opening on the refrigerator casing. In some instances it may be carried at the rear side of the door, when the door is closed, the gasket should be compressed for an effective seal against the escape of air from within the refrigerator and the entrance of heat from the outside.

At the inner side of the casing 1 and close to the outer side or face of said side of the casing, a keeper 4 is permanently secured comprising a bracket 4 having a base and two spaced arms extending therefrom, between the free ends of

which a cylindrical pin or roller 5 is permanently secured.

In the latch structure, a housing of sheet metal integral in all of its parts, is used. It is formed with an inner side 6 (Fig. 11) of a generally rectangular form, from the longitudinal edges of which two spaced sides 7 are bent to extend outwardly. What may be termed the rear end of the housing, is closed by an end 8 which is an extension at one end of the inner side 6. At its other end, two tongues 9 are bent inwardly toward each other leaving a substantially rectangular opening 10 between their inner edges and the side 6. Each of the sides 7 at its outer edge has a flange 11 bent therefrom at right angles. The outer or base side of the housing is open except for an extension 12 to the rear end 8 which is bent to lie in parallelism with the inner side 6 and the length of which is less than the overall length of the housing as shown.

Within said housing, at its rear portion, a member which together with the latch bolt hereafter to be described, makes in effect a toggle lever is located. Such member made from a single piece of sheet metal has two spaced sides 13 connected at one end by an integral bridge 14 between them. Said sides 13, at their opposite ends, have pin-passing openings therethrough and are also formed each with an ear 15 as shown with like pin-passing openings in alignment with each other.

The latch bolt is also made from a single blank of sheet metal. It has an inner side 16 from which two spaced sides 17 are bent at right angles in an outward direction. At its forward end the inner side 16 is continued in an inclined or beveled end portion 18 for the bolt, and is bent back to provide an outer side 19 which is spaced from and lies generally in parallel relation to the inner side 16, being located at the free longitudinal edges of the sides 17, but of a lesser length than the inner side 16.

The sides 13 of the previously described member are located within the latch housing; and through them and openings in the sides 7 of the latch housing made therefor, a pivot pin 20 passes and is headed over at its ends. The pivot pin 20 is located in relatively close proximity to the inner side 6. The bolt at its beveled portion 18 at its outer end, passes through the opening 16 located at the front end of the housing and extends toward the ears 15. The sides 17 of the bolt have each formed therein a longitudinal slot 21 with closed ends. A pin 22 passes through the openings in the ears 15 and through said slots, thereby providing a pivotal and sliding connection of the latch bolt with the sides 13. A stop 23 is pressed inwardly from each of the sides 17 near the front end of the bolt, between which and the pin 22 a coiled compression spring 24 is located housed within the bolt. A second spring, a torsion spring 25, is around the pin 20 having the two arms thereof, one bearing against the side 6 of the housing and the other against the rear edge of the bridge 14. The normal tendency of said spring is to turn the member consisting of the sides 13 and the bridge 14 in a clockwise direction (Figs. 5 to 8 inclusive).

The part 12 which is at the outer side and rear end of the housing has an opening made therethrough with a short guide sleeve, as shown, around the opening, for the passage of a rod 26 which, when the latch bolt is in operative engagement with the keeper, as shown in Fig. 7, at its inner end within the housing, interposes a

stop back of the bridge 14 against the movement of said bridge and the connected sides 13 in a counter-clockwise direction.

The latch housing with the latch bolt within it, assembled as described, is secured at the inner side of the door 2. The rod 26, as shown in Figs. 1 and 2, passes through an opening made through the door to the front side thereof. At its outer end (Fig. 1), it may have a pivotal connection to a hand lever 27 pivotally mounted on a suitable fixture secured at the outer side of the door. A pull outward on the free end of the handle will withdraw the rod 26. Said rod is normally moved inward when free for such movement by a coiled spring 28 associated therewith, as shown in Fig. 1. Instead of the handle 27 being used to withdraw the rod 26, a suitable escutcheon 29 may be secured against the outside of the door and use may be made of the same screws which pass through the flanges 11 of the latch housing in connecting it at the inner side of the door to securely connect said escutcheon. The rod 26 at its outer end is equipped with a pull knob 30 adapted to be grasped by the hand to withdraw the rod 26 against a spring 31, as shown, which normally moves the rod 26 to its inner operative position.

With the door closed (Fig. 1), the outer end of the latch bolt bears upon the pin or roller 5 at its inner side with the parts of the latch mechanism as in Fig. 1 and also in Fig. 7. The rod 26 is at the rear edge of the bridge 14 so that the latch bolt can not disengage from the keeper except by a substantially direct longitudinal movement to the position shown in Fig. 6. Such longitudinal movement with the door closed can not take place, as there is no applicable force possible to thus move the latch bolt when, with the door closed, it is connected with the keeper. To open the door the rod 26 is pulled outwardly, as by operating the handle 27, the knob 30 or any other of an indefinite number of means which can be used for such purpose. On an outward pull and movement of the rod 26, it is moved out of the path of movement of the bridge 14 and the latch bolt and the member carrying the bridge 14 moves from the position shown in Fig. 7 to that in Fig. 8, substantially a breaking of the toggle lever structure being made, and requiring approximately only an overcoming of the strength of the spring 25. The latch bolt when thus tilted and drawn bodily inward will, at its outer end, pass by the keeper pin or roller 5 and the door may be opened, such opening following naturally by reason of the outward pull on the handle. As soon as the handle is released after opening the door, springs 25 and 28 will return the parts to the position shown in Fig. 5.

On closing the door the beveled outer end 18 of the latch bolt rides against said keeper member 5. The first movement is a movement of the bridge 14 from the position in Fig. 5 to that in Fig. 6, a very limited amount or until stopped by the rod 26. Thereafter spring 24 is compressed as the bolt is moved bodily inward until its outer end passes by the keeper member 5. In Fig. 6 it is shown at the initial stage of such passage.

After it has passed by said keeper member 5, spring 24 projects the latch bolt to the position shown in Fig. 7, the side 19 of the bolt riding against the inner side of the keeper pin or roller 5. It will be noted that the side 19 is not all in the same plane but that the outer portion is inclined slightly with respect to the inner portion providing in effect a wedging action under influence of the spring 24. The in-

ward movement of the door under such engagement of the slightly inclined outer end portion of the side 18 with the pin 5 is small, therefore, the force of the spring 24 is multiplied, in accordance with the principles of leverage, to compress the gasket at 3 and effect a very tight seal between the door and the refrigerator casing. The final position of the latch mechanism with the door closed, shown in Fig. 7, is with the bolt tilted to the longitudinal axes of the housing and with the inner or rear edge of the bridge at 14 against the pin 28, bearing thereagainst with pressure so that upon pulling the rod 26 outwardly, the latch has an initial movement toward its final opening position in Fig. 8, and is carried to complete keeper disengaging position shown in such figure, through the force exerted in pulling outwardly upon the handle or knob when the rod 26 is manually withdrawn plus the assisting force of the door gasket 3.

The structure described is of a very practical and simple form. By reason of the substantially complete housing of the spring within the latch bolt, the overall length of the latch is reduced. The number of parts used is at a substantial minimum. Door opening is rendered easy and the tight closing of the door is insured. The three major parts of the structure, all of sheet metal, may be produced economically by large quantity methods of fabrication. The assembly is very simple requiring merely the insertion of the spring 24 into the bolt, the connection of the bolt with the ears 15 by inserting the pin 22 through openings therein and the slots 21, and the location of the bolt and its connected member within the housing, and a passage of a pin 28 through the openings in the housing sides and at the outer corners of the sides 18 and through the middle portion of the spring 24, with the heading of the ends of said pin 28.

Simplicity of structure with resultant economy in manufacture, and durability in service are primary characteristics of the present invention, together with insured sealing of the closed door and releasing the latch bolt from its keeper for door opening with a minimum of release motion and effort.

The invention is defined in the appended claims and is to be considered comprehensive of all forms of structure coming within their scope.

We claim:

1. In a latch structure, a housing having spaced sides and having an end between said sides with an opening therethrough, a latch bolt located within the housing with a free end portion thereof adapted to pass through said opening, a member located within the housing of a generally triangular form, a pivot pin carried by the housing upon which said member is mounted for pivotal movement at one of its corners located inwardly a distance from the inner end of the bolt and near the edges of said sides, a pin extending through said member at another corner thereof located outwardly a distance from said first pin, said latch bolt having longitudinal slots for the passage of said pin therethrough, spring means housed in the bolt bearing at one end against second mentioned pin and at the other end, bearing against the bolt to normally hold the bolt in an outer position with respect to said member, said bolt being movable inwardly on compression of said spring with said member held against movement, and a movable stop means located adjacent the remaining corner of said member and back thereof to nor-

mally hold the member against movement, said movable member being adapted to be moved away from its normal position to release said member for pivotal movement.

2. A construction as defined in claim 1, said housing at a side thereof adjacent the remaining corner of said member having a section located between the edges of the sides of said housing and of less length than the length of the housing provided with a guide opening therethrough, said stop comprising a longitudinally movable rod extending through said opening back of said pivotally mounted member to hold it against movement, combined with yieldable spring means normally moving said rod in stopping position, said rod being adapted to be moved outwardly against the spring means acting thereon.

3. A latch structure including a housing of flat metal having parallel spaced sides, an inner side, an outer end having an opening therethrough and an inner end having a portion extending therefrom of less length than the length of said sides of the housing at the outer side thereof, said last mentioned section having a guide opening therethrough, a sheet metal bolt having a closed end of substantially rectangular form and four sides extending therefrom, the closed end of said bolt normally extending through said opening in the end of the housing, two sides of said bolt being located in parallel relation to the spaced sides of the housing and having longitudinal slots, one in each side, a member of sheet metal having two spaced sides and a bridge connecting said sides at one edge thereof, said sides being of substantially triangular form, one of the corners of each of said sides extending to the slotted sides of said bolt and located in side by side relation therewith, a pin extending through said corners and through the slots in said bolt, a coiled compression spring between said pin and the outer end of the bolt, a pivot pin extending through one of the other corners of said sides of said member and through the spaced sides of said housing located adjacent the inner side of said housing, said bridge between the sides of the member being located adjacent and normally forward of the guide opening in said housing, and a longitudinally movable rod extending through said opening back of said bridge and in the path of movement thereof normally stopping its movement toward the inner end of said housing, said rod being adapted to be moved outwardly and out of the path of movement of said bridge.

4. A construction as defined in claim 3, and a spring associated with said member exerting force thereon to move the bridge portion thereof in a direction away from said rod, and a second spring associated with the rod normally moving said rod to its stopping position, said second spring being yieldable for outward movement of the rod.

5. A latch structure comprising, an elongated housing substantially rectangular in cross section, having four sides and two ends, the outer end thereof having an opening therethrough, and a side extending from the inner end of the housing toward the outer end a part of the distance between said ends whereby one side of the housing is partially open, said latch housing being adapted to be secured at the inner side of a door with said last mentioned side of the housing closely adjacent the door, the opening at the inner end of the housing being spaced inwardly 75 from the door a short distance and extending

substantially to the inner side of said housing, a latch bolt having an outer closed beveled end and four sides extending from the edges of said end, having an inner side adapted to lie against the inner side of the housing, the two of said sides of the bolt located substantially perpendicular to the side of the door having longitudinal slots therein, said slotted sides of the bolt near their outer ends having inwardly extending projections, a spring within said housing bearing at one end against said projections, a member having two spaced sides, generally of triangular form, and a bridge connecting said sides at an edge thereof located adjacent the inner side of the door, said side of the member at one of the corners thereof, extending to and having overlapping relation with the slotted sides of said bolt, a pin passing through the sides of said member at said corners and through said slots against which the other end of the spring bears, a pivot pin extending through the innermost corner of the sides of said member and through adjacent sides of the

housing near the inner side of said housing, spring means around said pin engaging with the inner edge of the bridge and against the inner side of the housing normally moving said member in a direction toward said bolt, and a rod passing through the outer side of the housing inwardly of said bridge and against which the inner edge of said bridge may bear, said rod being mounted for longitudinal movement for movement away from said bridge and out of engagement therewith.
